UNITED STATES PATENT OFFICE.

JOSEPH M. STONE, OF NORTH ANDOVER, MASSACHUSETTS.

IMPROVEMENT IN SPINNING-FRAMES.

Specification forming part of Letters Patent No. 152,881, dated July 7, 1874; application filed February 10, 1872.

To all whom it may concern:

Be it known that I, JOSEPH MASON STONE, of North Andover, in the county of Essex and State of Massachusetts, have invented certain Improvements in Spinning-Machines, of which the following is a specification:

My invention relates to the construction of that part of a spinning-machine which supports the spindles, and receives the bearings in which they revolve, and to other parts working in the same connection, by which improvements the spindles are more accurately held in position, and the parts are more conveniently and cheaply made. One of my improvements consists of a new mode of fastening the spindle-step, as will be described. Another improvement consists in splitting the partitions between the sockets that receive the spindle-steps, or the bolsters in the spindle-rails, or the rings in the coppering-rail, so that, by forcing in the steps or parts to be held, moderately, they will be held in place by the elasticity of the socket, or by contracting it by a screw, as will be described. Another improvement consists in the formation in the lower rail of an oil pan or reservoir, which receives the waste oil from the steps of the spindles, and from which also I propose to oil the steps, if desired. Another improvement consists in forming the sockets or sleeves for the guide-rods, which carry the coppering-rail, in one piece with the spindle-rails, as will be described; and also in a new method of forming the bearing-surfaces in said sockets, in which the guide-rods work. Another improvement consists in the use of thin sliding panels or doors to close the space between the spindle-rails in front of the spindles, which doors slide in grooves in the spindle-rails, as will be described.

In the drawing, Figure 1 is a front elevation of the spindle-frame and parts connected therewith, with a part of the lower rail in longitudinal section. Fig. 2 is a rear elevation of the same. Fig. 3 is a horizontal section above the lower rail. Fig. 4 is a cross-section through the center of a spindle, with spindle-bearings of the usual form. Fig. 5 is a cross-section through the center of one of the guide-rods of the coppering-rail. Fig. 6 is a top view of a portion of the upper spindle-

rail, and Fig. 7 is a top view of a portion of the coppering-rail of the preceding figures. Fig. 8 is an enlarged vertical section of the spindle-frame fitted with my improved ring, and bolster, and step. Fig. 9 is an enlarged view of Fig. 5, to show more clearly its construction. Figs. 10 and 11 are detached views of a portion of the coppering-rail fitted with my improved rings. Figs. 12 and 13 are detached views of a portion of the lower spindle-rail fitted with my improved steps.

A is the upper spindle-rail, and B is the lower rail, which are both made in one piece, being connected at the back side by the small cross-bars *a*, between each two spindles, or at such intervals as may be desired, and the sockets or sleeves *b*, which receive the guide-rods C, which carry the coppering-rail D, and the feet *e*, by which the rails are attached to the end frame of the machine. For distinction in this description, I call this self-contained part of the machine the spindle-frame. The bearings and steps of the spindles may be made and secured to the rails in any usual way, or modified, as will be described. E E, &c., are the spindles; and F F, &c., are the whisks by which they are driven, as usual. The spindles are shown as working with the ring and traveler, so called; but the improvements described may be used in connection with spindles working either with or without fliers, with the same advantages. F' is the bolster or upper bearing of the spindle, which may be fitted into the upper rail A in the usual way, or as is shown in Fig. 6. It is formed with a part, *g*, which extends below the upper rail nearly to the whisk F, and serves as a stop to prevent the spindle from being raised when the bobbin or cop is drawn off. By this construction, the necessity of making the spindle with an enlarged part, so as to form a shoulder beneath the bolster, to prevent the spindle from rising, as is usual, is avoided, and the spindles can be made lighter, with equal efficiency in operation. The part *g*, also, by its contiguity to the whisk, takes the lateral strain of the driving-band *f*, without tending to bend the spindle, and also gives a very large wearing-surface to the bearing. The driving-bands lead from the whisks to the main drum through the openings between the

bars *a*, as is shown by the dotted lines *f* in Fig. 4. Each of the bosses *H'* of the lower rail *B*, which receive the steps *H*, may be sawed through lengthwise of the rail at *h*, to the bottom of the socket, so that the socket will yield slightly when the step *H* is forced into it, and thereby hold the step with sufficient firmness without any other fastening, and, at the same time, without straining the rail out of shape, and saving the cost of the set-screws usually employed for securing the steps. The bolsters *F* and the rings *M* may also be secured in a similar manner to the rails *A* and *D*, respectively, as is seen more particularly in Figs. 6 and 7, in which a slit, *i*, is cut between alternate sockets, as shown, or slits may be made between several sockets in succession, leaving a sufficient number of the spaces between the sockets solid to preserve the strength of the rail. If a further security is required, screws may be put in between the sockets through the slits, as shown, which will further gripe the socket upon the bolsters or rings, as the case may be, if desired.

The ring *M*, as shown in Fig. 8, is of a **T** form, in cross-section, and is set into a shouldered recess in the coppering-rail, as is shown.

In Figs. 8 and 12 is shown my improved spindle-step. It is made with a cylindrical shell or casing, *Q*, provided with a shank at the lower end, to set in the lower spindle-rail, which shank, in its axis, receives a small screw, *m*, which passes up through a hole in the rail from beneath, as is shown, and serves to hold the shank into its socket in the rail, and when the screw is removed it enables the step to be driven out by means of a drift which is inserted through the hole. *R* is a piece of composition, or other suitable metal, of the form shown in section, which forms the bearing for the spindle. At its ends the piece *R* is made to fit the cylindrical cavity in the shell *Q*, but the intermediate portion of its surface is removed, which leaves a cavity or space, *S*, between its surface and the interior of the shell to form a chamber for oil. This space is connected with the bearing of the spindle by holes, as shown in Fig. 8, or by cutting away a portion of one side, as is shown at the right hand in Fig. 12. The holes or spaces open toward the front of the machine, so that the side that sustains the draft of the band may be entire. By this construction the entire surface of the piece *R*, both inside and out, can be finished in the lathe.

The lower rail *B* is made with a recess or oil-pan, *I*, as shown, which catches the oil from the steps of the spindles; and I also contemplate oiling the foot of each spindle from this, by so forming the steps *H* that the oil will flow into the bearings from the oil-pan *I*, through the slit *h*, or a hole formed for the purpose, in an obvious manner. The guide-rods *C* are fitted to slide accurately through

the sleeves *b* of the spindle-frame, and are attached to the coppering-rail *D*, and to the mechanism for raising and lowering the same, in any usual way employed where a coppering-rail is used; but in mules and jacks the coppering-rail and its adjuncts would be omitted. The method in which I propose to make the bearings for the guide-rods in the sleeves *b* is shown in Figs. 5 and 9, in which the hole through the sleeve is made somewhat larger than the guide-rod, and the space between them is filled with a lining of soft metal, such, for instance, as an alloy of lead or tin, which is cast into the sleeves around the guide-rod, after it has been accurately placed in position, making a very cheap and excellent bearing. I propose to place the guide-rods in position in the sleeves by means of the templet or frame, by which the boring of the sockets of the several spindle-bearings is directed. *K K* are sliding doors or panels, which slide in grooves in the upper and lower spindle-rails, as is shown in Figs. 3, 4, and 5, to close the space between the rails in front of the spindles. The doors are made in lengths of about four feet, more or less, and are alternately placed in and out, as is shown, so as to slide past each other, by which arrangement all the spindles are accessible. I propose to make the panels of Russia sheet-iron.

By this mode of construction, the spindle-frame, with the parts attached thereto, can be entirely completed before the spindle-frame is placed in the machine, and the holes for the bearings in the several rails can all be bored at the same time, by means of a suitable templet, at one operation, so that all the holes will be truly concentric, and the relation between the upper and lower bearings of the spindles will be accurately preserved, even if the spindle-frame changes its form or position; and the economy and convenience of fitting the work to the spindle-frame while detached from the machine are very important.

What I claim is—

1. The screw *m*, in combination with the shank of the spindle-step, for the purpose of confining the same in the spindle-rail, substantially as described.
2. The split partitions between the sockets, for holding a spindle-step, bearing bolster, or ring, substantially as described.
3. The oil-pan *I*, in combination with the lower spindle-rail, substantially as described.
4. The sockets or sleeves *b*, in combination with the spindle-rails, and connecting the same, substantially as described.
5. The sliding panels or doors, in combination with the spindle-rails, substantially as described.

Executed February 7, 1872.

JOSEPH M. STONE.
